UNITED STATES PATENT OFFICE

CARL C. MULDNER, JR., OF MAPLEWOOD, MISSOURI

PORTFOLIO FOR NECKTIES AND SOFT COLLARS

Application filed August 5, 1929. Serial No. 383,665.

My invention relates to a portfolio for neckties and soft collars, and has for its object to provide a portfolio or folder provided with a plurality of inner pockets for the reception of neckties and soft collars for retaining them in a folded flat condition in a traveling bag, drawer, or the like.

A further object of the invention is to provide a portfolio of the above class which is made from a single sheet of paper, leather, or other flexible material, thereby economizing in material.

A still further object of the invention is the provision of a portfolio for neckties and soft collars, which possesses advantages in points of simplicity and efficiency and, at the same time proves itself comparatively inexpensive in cost of manufacture.

The above and other objects, the invention attains by the construction hereinafter described and illustrated in the accompanying drawings, wherein:

Fig. 1 is an inside plan view of the blank before it is folded.

Fig. 2 is a plan view with upper inner cover sections of the blank folded back over the outer cover sections.

Fig. 3 is a plan view with both the upper and lower inner cover sections folded back upon the outer cover sections.

Fig. 4 is a plan view with the side flaps of the outer cover sections folded back over the side edges of the upper and lower inner cover sections and showing neckties and soft collars inserted in the pocket openings.

Fig. 5 is an end elevation of the portfolio in final folded position.

Fig. 6 is a sectional elevation taken on line 6-6 of Fig. 1.

Fig. 7 is a sectional elevation taken on line 7-7 of Fig. 1.

In carrying out the aim of my present invention, I employ a single blank or sheet of flexible material, such for instance as paper, leather, or any other similar material.

The blank or sheet is longer than it is wide and is substantially rectangular in shape.

As shown in Fig. 1, the blank is provided with the transverse score lines 1 and 2 to divide the blank into three general sections,

namely, the upper section 3, the lower section 4 and the middle section 5. The upper section 3 is of less area than the lower section 4, or in other words, the score line 1, is nearer the edge 6 of the upper section than the score line 2 is to the edge 7 of the lower section 4.

The middle section 5 is provided near its side edges with the score lines 8 and 9 which are in alignment with the opposite side edges of the upper and lower sections 3 and 4, thereby providing the side edges of the middle section 5 with the opposed flap sections 10 and 11.

The upper and lower sections 3 and 4 are provided midway their side edges with the embossed sections 12 and 13, respectively, and the middle section 5 is provided midway its side edges and in alignment with the embossed sections 12 and 13, with an embossed section 14. The latter embossed section 14 is reversed from the embossed sections 12 and 13 so that when the upper and lower sections are folded over and upon the middle section 5, the embossed sections 12 and 13 will nest into the embossed section 14 of the middle section 5 to provide a relatively stiff back section for the portfolio.

The embossed section 14 of the middle section 5 divides the middle section into two like outer cover sections designated 15 and 16. The embossed section 12 of the upper section 3 divides the upper section 3 into two like upper inner cover sections 17 and 18 and the embossed section 13 of the lower section 4 divides the lower section 4 into two like lower inner cover sections 19 and 20.

The upper inner cover sections 17 and 18 are provided with a plurality of aligned transverse slotted openings 21 and 22, respectively, near the end edge thereof. Likewise, the lower inner cover sections 19 and 20 are provided with a plurality of aligned transverse slotted openings 23 and 24, respectively, near the end edge thereof, all of which are clearly shown in Fig. 1.

To form the portfolio, first, the upper section 3 of the blank is folded on the score line 1 so as to lap over upon the upper portion of the inner face of the middle section 5. The embossed section 12 is secured to the

embossed section 14 of the middle section 5 by means of a suitable adhesive. Second, the lower section 4 of the blank is folded on the score line 2 so as to lap over and upon the lower portion of the inner face of the middle section 5 and with its slotted end portion overlapping the slotted end portion of the upper section 3 to which it is adhesively secured so that the slotted openings 23 and 24 of 10 the lower inner wall sections 19 and 20, respectively, will register with the slotted openings 21 and 22 of the upper inner wall sections 17 and 18, respectively. By overlapping and adhesively securing the free ends 15 of the upper and lower inner cover sections stiffens the material along the edges of the transverse slotted openings, making it easy to insert ties and soft collars into the cover pockets through the openings, as it reinforces 20 and slightly stiffens the edges of the openings and prevents their edges being easily torn, or injured.

Next, the side flaps 10 and 11 are folded upon their score lines 8 and 9, respectively, 25 and engage the inner side edge faces of the inner cover sections 17 and 19, respectively and 18 and 20, respectively, to which they are adhesively secured, thereby enclosing the side edges of the cover sections of the portfolio and providing a single pocket or space 30 between the outer and inner cover sections of each cover of the portfolio, which can be entered through the registered slotted openings 35 of the inner cover sections of the portfolio, as will be apparent from Figs. 3 and 4 of the drawing.

Articles, such as neckties and soft collars, as well as other flat articles, if desired, can be inserted into the pockets through the openings from either direction, as is manifest. 40 It will be noted, however, that the pockets are deeper upon the lower side of the openings than from the upper side thereof, as clearly shown in Figs. 3 and 4.

45 In practice, neckties, designated 25 are mounted upon a suitable card 26 by folding the neckties thereof before inserting them through the openings into the pocket between the inner and outer sections of the portfolio.

50 Soft collars are stiff enough when folded midway their ends to be inserted into the cover pocket through the openings in the inner cover sections without being mounted upon a card.

55 From the foregoing description, it is evident that I provide a portfolio, or holder for neckties and soft collars, or other similar articles, which are to be kept in a pressed flat condition, that can be conveniently carried in a handbag, suitcase, or the like without danger of their being wrinkled or becoming misplaced and that the portfolio can be packed with other articles without danger of breaking the portfolio due to the fact that 60 it will flex if packed in an uneven place owing

to the fact that the portfolio material is of a flexible nature.

The many advantages of the herein described invention will readily suggest themselves to those skilled in the art to which it 70 appertains.

From the foregoing description, it is evident that a simple device for this purpose has been disclosed, but it is to be understood that I do not desire to restrict, or limit myself 75 to the very details of the construction shown and described, which is merely illustrative, it being obvious that changes, not involving the exercise of invention, may be made without conflicting or departing from the spirit 80 of the invention within the scope of the appended claims.

What I claim is:

1. In a portfolio of the class described 85 formed from a single sheet of flexible material and embodying a pair of flexible cover sections each comprising a one piece outer wall and a two piece inner wall embossed at their inner edges and adhesively secured together to provide a relatively stiff back 90 section, the ends of the two piece inner walls being overlapped and adhesively secured together to slightly stiffen the inner walls transversely at this point, the overlapped ends of the inner cover walls being provided 95 with aligned transverse openings leading to the space between the outer and inner walls of the cover sections and the side edges of the outer walls being folded over and adhesively secured to the side edge portions of 100 the two piece inner walls of the cover sections.

2. A blank of flexible material for the formation of a portfolio comprising a rectangular sheet of material, a pair of spaced transverse 105 score lines dividing the sheet into an intermediate section and two end sections, the two end sections being embossed to divide each end section into two inner wall sections, each inner wall section being provided near its end edge with a plurality of aligned transverse slotted openings, the intermediate section being embossed to divide it into two outer wall sections and the side edge portions 110 of the outer wall sections each being scored 115 to provide a side flap for each outer wall section.

In testimony whereof, I have hereunto affixed my signature.

CARL C. MULDNER, JR.
